UNITED STATES PATENT OFFICE.

FREDERICK C. OWEN, OF FAYETTEVILLE, NORTH CAROLINA.

METALLIC ARC-WELDING APPARATUS.

Application filed February 12, 1925. Serial No. 8,790.

This invention relates to transformers, and more particularly to transformers especially designed for use in connection with electric arc welding apparatus.

5 The invention has for one of its objects the provision of a transformer of the character stated which will reduce to the minimum the rise and fall of the amperage delivered to the electrode of an arc welding 10 apparatus and which will prevent fluctuations in the flow of current to the electrode, with the result that an arc which is uniform and will not burn the metal being welded may be easily maintained.

15 A further object of the invention is the provision of a transformer of the character stated which will efficiently function without damping devices, rheostats, resistances of all kinds and similar devices now employed in connection with arc welding apparatus, whereby to reduce to the minimum the cost of manufacturing and the operating expense of arc welding apparatus.

With the above and other objects in view, 25 the invention consists of the combination and arrangement of parts hereinafter fully described and claimed, and illustrated in the accompanying drawing, wherein:

The figure is a diagrammatic view of an 30 arc welding apparatus embodying my improved transformer.

As shown in the drawing, the transformer comprises a laminated core 1 which is preferably of oblong formation. The primary 35 circuit of the transformer comprises sections or coils 2, 3 and 4 arranged in series on three adjacent legs of the core. The coils 2 and 4 are mounted on the short limbs, and coil 3 on one of the long limbs of the core 1. The 40 coils 2 and 4 preferably have a similar number of turns or convolutions and may be termed auxiliary coils, and the coil 3 has a greater number of turns or convolutions than one of the other coils and may be 45 termed the primary coil. Leads 6 and 7 extend from the coils 2 and 4 to a switch 5, and leads 8 and 9 extend from any suitable source of current supply to the switch.

The secondary circuit of the transformer 50 comprises a main section or coil 10 which is mounted on the long limb of the core 1 that carries the primary coil 3, and an auxiliary section or coil 11 mounted on the other long limb of the core. The coils 10 and 11 55 are reversely wound or reversely connected, and are connected in series by a wire 12 so

that their voltages are added. The coil 11 has a greater number of turns or convolutions than the coil 10, and extending from certain turns or convolutions thereof are 60 tap leads 12. These leads are connected to the contact jaws 13 of a switch 14, the blade 15 of which is pivotally and rotatably mounted. A lead 16 extends from the switch blade 15 to an electrode 17 which is shown 65 secured in a carrier 18. A lead 19 extends from the coil 10 to the contact jaw 20 of a switch 21 the blade 22 of which is grounded, and a lead 23 extends from the wire 12 to the other contact jaw 24 of this switch. A 70 lead 25 extends from one of the convolutions of the coil 10 to the contact jaw 26 of the switch 14. The table 27 of the arc welding apparatus is, as shown in the drawing, 75 grounded.

The switch 21 permits either end of the coil 10 or one end of coil 11 and one end of coil 10 to be grounded. When the blade 22 of this switch is in contact with jaw 20 and the blade 15 of the switch 14 is in contact 80 with one of the jaws 13, a secondary circuit is established which includes the coil 10, certain of the turns or convolutions of the coil 11 and the electrode 17. When the blade 22 is in contact with jaw 24, and the blade 15 85 in contact with one of the jaws 13, a secondary circuit is established, which includes certain of the turns or convolutions of the coil 11 and the electrode 17, and automatically cuts out coil 10. When it is desired to 90 weld a small article, the blade 22 is swung in contact with jaw 24, and the blade 15 in contact with one of the jaws 13. When it is desired to weld a medium or heavy article 95 the blade 22 is swung in contact with jaw 20, and the blade 15 into contact with jaws marked 13, while when it is desired to fill the scores of an engine cylinder with metal, the blade 22 is swung in contact with jaw 20 and the blade 15 into contact with jaw 26, which 100 automatically cuts out coil 11 and a current of three to four hundred amperes flows to score filler rod when contact is made with cylinder.

Current flowing through the coils 2, 3 and 105 4, constituting the primary winding, tends to cause a magnetic flux to circulate through the four legs of the core 1. Practically all the flux developed by this primary winding will thread the main secondary winding section or coil 10, because of the close association of this secondary coil with the primary, 110

and flux in this part of the core remains substantially constant at all loads. As a result, the voltage generated in this secondary coil 10 likewise remains practically the same 5 at all times, and does not vary with the load.

The auxiliary section or coil 11 of the secondary winding, however, being remote from the primary winding, tends to set up a flux independent of and opposed to that generated by the primary winding. Owing to the location of the coils, this secondary flux is confined substantially to that leg of the core on which the coil 11 is mounted. The primary flux threads the other three legs of 15 the core, and also tends to permeate the fourth leg. In this fourth leg, however, it is opposed and choked back by the flux due to the secondary winding 11. By reason of the shape of the core and position of the separated primary windings on three legs thereof, there will be a certain amount of flux leakage from each end of the primary coils 20 and 4. Owing to the opposing and choking effect of the secondary coil 11, however, a 25 very exaggerated leakage takes place at the two lower corners of the core, or, in other words, by far the greatest proportion of flux is forced out of the closed metallic path into the air at these points. The larger the current drawn from the secondary winding, the 30 greater this leakage becomes.

As a result of such leakage, the heavy secondary flux causes the coil 11 to develop high inductance, and act as an impedance coil, so 35 that the phase of the voltage in this part of the secondary winding is shifted. The resultant voltage at the arc is therefore reduced, or at least prevented from increasing, as the current increases. The impedance 40 action increases with the load, so that, even on short circuit, it serves to prevent an excessive or dangerous flow of current. Thus a stable arc is maintained.

These transformers are to be built to op-

erate on either single or three phase alternating current, and are to be inclosed in either wood, cast iron, steel or aluminum cases, and are to be oil insulated and cooled, or air cooled. 45

From the foregoing description, taken in connection with the accompanying drawing, it should be understood that I have provided a transformer which will deliver the desired amperage to the electrode 17. The apparatus is highly efficient and does not require the use of damping devices, rheostats, resistances and similar devices, and will enable an arc which will be uniform and will not burn the metal being welded to be easily maintained. 50

What is claimed is:—

1. Apparatus for metallic arc welding comprising a transformer having a closed circuit rectangular core, a primary winding embodying a main section and auxiliary sections mounted on three adjacent legs of the core, said main section having a greater number of turns or convolutions than each of the auxiliary sections, and a secondary winding embodying a main section wound on the middle one of said three legs and an auxiliary 65 section mounted on the opposite leg of the core. 70

2. Apparatus for metallic arc welding comprising a transformer having a rectangular core, a primary winding distributed on three adjacent legs of the core, a secondary winding embodying a main section on the middle one of said three legs and an auxiliary section on the opposite or fourth leg 75 of the core, an electrode connected to the auxiliary section, a wire connecting the adjacent ends of said sections, ground leads extending from the opposite end of said main section and from said wire, and a switch by means of which either of said leads may be 80 grounded. 85

In testimony whereof I affix my signature.
FREDERICK C. OWEN.
